CAP FEEDER

Frank W. Krueger, Atherton, Calif., assignor to
Food Machinery Corporation, San Jose, Calif.,
a corporation of Delaware

Application July 3, 1944, Serial No. 543,338

4 Claims. (Cl. 226—88.1)

1

This invention relates to feeding devices and particularly to devices for feeding flat articles individually from a stack of such articles.

It is an object of my invention to provide a novel and efficient means for feeding relatively flat articles from the bottom of a stack of these.

It is another object to provide such a feeder in which a relatively tall stack of articles may be placed in the magazine without jamming the feeding mechanism.

Another object of the invention is to provide such a feeder adapted to feed closures for containers in which the application of the closure is done in an automatic machine and which will feed closures to said machine in timed relation with containers fed thereto but will omit the feeding of a closure to said machine whenever the feeding of a container thereto is omitted.

The manner of accomplishing the foregoing objects as well as further objects and advantages will be made manifest in the following description taken in connection with the accompanying drawings in which:

Fig. 1 is a plan view of a preferred embodiment of the invention incorporated with the jar capper disclosed in my co-pending application for U. S. Letters Patent, Serial No. 543,336, filed July 3, 1944, on Method of and apparatus for capping containers.

Fig. 2 is an enlarged sectional view of a vacuum valve of the invention and is taken on section line 2—2 of Fig. 1.

Fig. 3 is an enlarged detail sectional view of the yieldable cap positioning finger of the invention and is taken on the line 3—3 of Fig. 1.

Fig. 4 is an enlarged vertical sectional view taken on the line 4—4 of Fig. 1 and showing the cap feeding prongs feeding a cap transversely from between the magazine thereof and the vacuum cup thereof.

Fig. 5 is a view similar to Fig. 4 and illustrates the cap feeding prongs in retracted position and with the vacuum cup pressed against the lowermost cap in the magazine at the upper end of its stroke.

Fig. 6 is a fragmentary cross sectional view taken on line 6—6 of Fig. 5.

Fig. 7 is a horizontal sectional view taken on the line 7—7 of Fig. 4.

Fig. 8 is a fragmentary sectional view taken on the line 8—8 of Fig. 5 and with the elements of the feed device positioned as in Fig. 5.

Fig. 9 is a view like Fig. 8 and illustrates the positions of the elements of the device at the moment the cup breaks vacuum with the lowermost cap in the magazine.

Fig. 10 is a vertical transverse sectional view taken on the line 10—10 of Fig. 7.

Referring specifically to the drawings and particularly to Figs. 1, 4, 5, 7 and 10, my invention

2

is there shown as embodied in a cap feeder 12 which is incorporated with and serves to feed caps to a rotary jar capper 13.

The capper 13 includes a capping rotor 14 having capped heads 15 equipped with cap chucks 16. The rotor 14 rotates in the direction of arrow 17 so as to cause the heads 15 to sweep over a cap transfer disc 18 having cap indexing pins 19. The disc 18 is mounted on a vertical shaft 20 which rotates in timely relation with the rotor 14 so as to present a cap 21 beneath each of the capping heads 15 just as the cap chuck 16 thereof moves downwardly in vertical alignment with this cap. The chuck picks up this cap and retains it in this head as the latter moves away from over the disc 18.

The disc 18 has a flange 23 lying flat against the upper face of the disc 18 and secured thereto. The shaft 20 journals in a bearing 25 to which is attached a cover plate 28 which overlies the disc 18 and supports a downward extending arcuate guard 29 spaced concentrically from the flange 23 so as to just allow a cap 21 to pass therebetween. Secured to the lower end of a pin 35 which is pivotally mounted in a boss 36 provided on the cover plate 28 is an arm 37 which is yieldably rotated by a spring 38 coiled about the pin 35 to position each cap 21 uniformly inwardly against the flange 23 and against a following pin 19 as these caps are carried with the disc 18. The arm 37 has a lug 42 carrying an adjustable stop screw 43 which bears against the cover plate 28 to limit the inward position of the arm 37.

The jar capper 13 has a jar feeding device 44 including tracks 45 and side rails 46 for holding jars 47 on the tracks, the latter being spaced to accommodate a conveyor chain 48 having upstanding, spaced lugs 49 for propelling jars 47 along tracks 45. The chain 48 is trained about the rotor 14 and is so timed in relation therewith that each lug 49 feeds a jar 47 beneath a certain one of the capping heads 15 as this lug travels toward the rotor 14.

A suitable means (not shown) is preferably employed for automatically placing jars 47 in the spaces ahead of the respective lugs 49. This means is not infallible, however, and occasionally a jar is lacking in a space immediately ahead 50 of one of the lugs 49 as this arrives at the rotor 14.

Pivotedly mounted on a vertical bolt 50 provided on the jar capper frame 27 is a jar responsive arm 51 having a short arm 52 extending therefrom towards the jar feeder 44. Also provided on the capper frame 27 is a stop pin 53 which limits the inward swinging of the jar responsive arm 51.

The cap feeder 12 performs the function of feeding caps 21 onto the transfer disc 18 so that

they will be delivered by the latter to each of the capping heads 15 which in turn apply these caps to the jars 47 delivered to the rotor 14 by the jar feeder 44. The cap feeder has a housing 58 which is mounted on the capper frame 27. This housing includes a gear box 57 and a cam box 58. Extending upwardly into the gear box and journaling in a bearing 59 therein, is a shaft 60 having a sprocket 61 thereon. This shaft is rotated by a chain 62 trained about the sprocket 61, this chain being operatively connected by suitable means (not shown) with the feed conveyor chain 48 so as to drive the cap feeder 12 in timed relation with the capper 13. Fixed on the upper end of the shaft 60 is a spiral gear 63 which meshes with a mating spiral gear 64 on a horizontal shaft 65 journaling in a bearing 66 in the gear box 57 so as to rotate a sprocket 67.

Journaled in bearings 70 and 71 in the cam box 58 is a cam shaft 72. Fixed on the shaft 72 is a cylindrical cam 73 and a sprocket pinion 74, the latter being connected to the sprocket 67 by silent chain 75 trained thereabout. Provided in the gear box 57 is an idler 76 which bears against the chain 75 and keeps this taut. Formed in the cylindrical surface of the cam 73 is a cam groove 78.

Formed internally in the cam box 58 is a boss 79 having a vertical bore 80 therein with a counterbore 81 in its upper end. Secured in place in the bore 80 as by screws 82 is a bushing 83. Extending through the boss 79 and the bushing 83 is a vacuum duct 84 and a vacuum release passage 85. Vertically slideable within the bushing 83 is a tubular vacuum cup plunger 86, the lower end of which is internally threaded to receive a cap screw 87 which secures a pin block 88 to the lower end of the plunger 86. Formed on this block is a crank pin 89 which is connected by a crank 90 with an eccentric 91 fixed on the adjacent end of the shaft 72.

The plunger 86 has a port 95 controlling the formation and releasing of vacuum within the plunger. The upper end of the plunger is internally threaded to receive a threaded sleeve 96 in which is mounted a vacuum cup unit 97. This unit includes a flanged hollow stem 98 which is slideable in the sleeve 96. A flanged collar 99 rests on top of the stem 98 and a cap screw 100 extends downwardly through this collar and is screwed into the threaded upper end of stem 98 so as to centrally grip and support a vacuum cup 101 at the upper end of the unit 97. Disposed within the cup plunger 86 is an expansion spring 102 which yieldably holds the unit 97 in its upwardmost position in the sleeve 96 as shown in Fig. 4.

As shown in Figs. 1, 2 and 4, a vacuum control valve 110 is provided having a bore 111 in which a plunger 112 is slideable, this plunger having a stem 113 and a spring 114 is coiled about the stem between the plunger 112 and an internal shoulder 115 formed at one end of the valve 110. The plunger 112 has an annular passage 116 formed therein which when the spring is compressed as shown in Fig. 2 is moved into position to connect a vacuum line 117 which leads to a vacuum pump (not shown) and a line 118 which connects with the vacuum duct 84.

The stem 113 is connected as by a wire 119 to the short arm 52 so that the spring 114 pulls the jar responsive arm 51 into broken line position as shown in Fig. 1 when no jar is opposite this arm on the tracks 45. This closes the valve

110 and shuts off the connection between vacuum lines 117 and 118. When a jar 47 is opposite the arm 51, however, as shown in full lines in Fig. 1, this arm is swung to pull the plunger 112 into the position in which it is shown in Fig. 2 in which vacuum lines 117 and 118 are connected.

Referring now to Figs. 4 to 10 inclusive, it will be seen that the cam box 58 has a top wall 124 which unites with the upper end of the boss 79, this top wall having a central opening 126 formed longitudinally therein and the upper portions of edges of this opening are milled away to provide a pair of opposed parallel slide flanges 127 (see Fig. 6) and guide shoulders 128 which unite to form a cross-head slideway 129. Just over the crank 81 and bearing 70 is lifter guide plate 130 which is held in place by screws 131, the latter being received in suitable threaded holes formed in the slide flanges 121. This plate has a central boss 132 through which a vertical guide bore 133 extends. This guide bore slideably receives a cylindrical lifter 134, the lower end of which is provided with a contact flange 135 and the upper end of which is provided with a lifter extension screw 136. The lifter 134 normally rests in its downward position shown in Fig. 4 in which the flange 135 engages bearing 70.

Seated in the slideway 129 is a crosshead 138, the body of which extends above the upper face of the top wall 124 and which has a downward extending boss 139 on which is carried a cam responsive roller 140 which extends into the cam groove 78.

Provided on the upper face of the crosshead 138 is a pair of longitudinal grooves 141 which receive shanks 142 of cap feed fingers 143, said fingers resting slideably on the upper face of the plate 130. The finger shanks 142 are secured in place on the crosshead as by flathead screws 147. Secured downwardly onto the top wall 124 as by cap screws 149 are gib plates 150 and a cap plate 151 (see Fig. 6). The gib plates 150 slideably hold the crosshead 138 in the slideway 129 and thus complete the latter. It is now to be noted that the cap feeder 12 is mounted on the jar capper 13 so that the upper face 125 of the top wall 124 is disposed just a slight distance above the surface of the cap transfer disc 18 (see Figs. 4 and 5). As the upper face of the plate 130 is flush with the upper surface 125 of the top wall 124, the cap feed fingers 143 operate slideably above and in sliding contact with the surface 125.

Formed on the cam box 58 is a hinge lug 152 carrying a pin 153 on which is pivotally mounted a cap magazine 154. This magazine has a tubular body 155 carrying hinge lugs 156 which straddle the lug 152 and are pivotally connected thereto by the pin 153. Secured to the upper end of the body 155 as by cap screws 157 is a collar 158 having guide rods 159 for holding a stack of caps 21 at an inclined angle for feeding these into the upper end of the body 155. Secured to the cam box top wall 124 by a screw 165 is a spring latch 166 carrying a dog 167 which is yieldably held over the collar 158 to retain the lower mouth of the magazine 154 flush against the upper surface 125 of the top wall 124 (see Figs. 8 and 9). The magazine body 155 has opposed vertical sight slots 168 and at right angles thereto is provided with shorter slots 169. Mounted on suitable bearings near the upper end of the body 155 are shafts 172, each shaft carrying a claw 173 and an arm 174 which are provided with bolts 175. Connecting the bolts 175 loosely is a link 176, this receiving

one of the bolts 175 through a slot 177 and having a central horizontal flange 178. This flange is disposed directly above the adjustable extension screw 136.

The magazine body 155 also has four openings 180 formed therein adjacent the bottom edge thereof. Pivotally mounted between lugs 181 disposed above each of the openings 180 is a stripper jaw 182 through which a bolt 183 fixed in the body 155 freely extends. This bolt holds a compression spring 184 adjustably against the jaw 182 to press this inwardly through the opening 180. Extending through the jaw 182 is a set screw 185 which engages the body 155 and adjustably determines the distance which the jaw 182 extends inwardly through the opening 180. The jaws 182 are pivoted on bolts 186 provided in the lugs 181 and these bolts are used to anchor the lower ends of contractile springs 187, the upper ends of which hook through openings in the flange 178 so that these springs continually urge the claws 173 inwardly through the holes 169 excepting when the pull of these springs is opposed by the lifter 134 lifting the link 176 (see Figs. 4, 5, 8, 9 and 10).

The lower end of the magazine body 155 is cut away to form a passage 192 which is of the same width as the internal diameter of the magazine body 155. This passage extends parallel with the feed fingers 143 which are reciprocated through this passageway to eject caps therefrom as will be made clear hereinafter.

Hingedly mounted on the body 155 (see Fig. 4) so as to overlie the transfer disc 18 and rest on the hub flange 26 thereof is a cap hold-down plate 193.

Operation

As already stated, the cap feeder 12 is driven in timed relation with the jar capper 13 so as to feed caps 21 onto the cap transfer disc 18 so that a cap will be picked up by one of the capper heads 15 and applied to each of the jars 47 which are fed to the capper by the jar feeding device 44.

Before the jar capper is started, a stack of the caps 21 is placed in the cap magazine 154. When these caps are first inserted, the claws 173 are manually swung outwardly to permit the caps to gravitate downwardly until the lowermost of these engages the stripper jaws 182 adjacent the lower end of the magazine. The claws 173 are then released so that these are swung inwardly yieldably by the action of the contractile springs 187. These claws thus engage and support all of the stack of caps in the magazine excepting a relatively small group of these caps which are disposed between the claws 173 and the lower inwardly extending ends of the stripper jaws 182. The jaws 182 are thus relieved of the weight of more than a small group of caps. This makes it possible to use springs 184 which are relatively light with the result that the lowermost cap in the magazine may be easily stripped downwardly past the stripper jaws 182.

When the capper 13 is started so that the rotor 14 rotates and the chain 48 propels jars 47 along the feeder 44 to the machine, each jar, as it passes the arm 51, moves this into its full line position as shown in Fig. 1. This results in the feeding of a cap by the cap feeder 12 to the jar capper 13.

The drive of the cap feeder 12 is such that the shaft 12, cam 73 and eccentric 91 make one revolution each time one of the pins 19 on the cap transfer disc 18 moves into position to engage a cap fed onto disc 18. The rotation of the cam 73 causes a reciprocation of the crosshead 138 so as to extend the cap feeder fingers 143 through 75

the cap feeding passage 192 as shown in Fig. 4, to push a cap 21 from this passage onto the transfer disc 18 just in advance of each of the pins 19 providing, of course, that a cap is disposed in the passage 192 at the time the fingers 143 are thus extended through such passage.

The delivery of caps from the magazine 154 into the passage 192 is accomplished by the vacuum cup 101 which operates as follows: With each rotation of the eccentric 91 the cup plunger 86 reciprocates between its lowermost position, as shown in Fig. 4, and its uppermost position, as shown in Fig. 5. In its uppermost position the cup 101 is pressed against the flat surface of the lowermost cap 21 in the magazine 154. If the arm 51 is at that moment engaged by a jar 47 on the jar feeding device 44 and swung outwardly into its full line position (shown in Fig. 1) this opens the valve 110 (as shown in Fig. 2) and causes a vacuum to be imposed through the duct 84 and port 95 on the interior of the plunger 86 which, of course, creates a suction between the cup 101 and the cap 21 engaged thereby. When the plunger 86 returns downwardly (as shown in Fig. 9) this suction strips the lowermost cap downwardly past the stripper jaws 182 and into the path of the prongs 143. As this stripping action is completed, the cap is simultaneously engaged by the prongs 143 and the vacuum in the cup 101 is broken by the port 95 coming opposite the vacuum release passage 85. The cap is thus released by the vacuum cup as it is thrust from the passage 192 by the prongs 143 into the position in which it is in Fig. 4, just in advance of an on-coming pin 19.

Each cap fed from the cap feeder 12 is delivered to that particular capper head 15 beneath which the jar feeding device 44 delivers the jar which engaged the arm 51 to cause this particular cap to be fed from the cap feeder. Thus if a jar is absent from in front of one of the chain lugs 49 of the feeding device 44 so that the arm 51 is not actuated as shown in Fig. 1 when this portion of the jar conveyor passes by this arm, the valve 110 will remain closed as vacuum cup 101 is next pressed against the lowermost cap in the magazine 154. This will mean that no vacuum is formed in this cup at this time wherefore the lowermost cap will not be stripped downwardly when the cup returns downward and no cap will be fed onto the transfer disc 18 during this cycle of operation of the cap feeder 12.

The advantage of this mode of operation is that none of the capper heads 15 will have a cap fed thereto when no jar is delivered beneath this capper head to be capped. Were a cap to be delivered to a capper head 15 and no jar presented to apply this cap to, the head would already have a cap in it when it again rotated into position to receive a cap from the disc 18 and the two caps would simply be mashed together when the head chuck 16 moved down to pick up the second cap.

While the claws 173 are spring pressed inwardly to support most of the caps stacked in the magazine 154, these claws are released with each cycle of the cap feeder by the crank 90 engaging the bottom flange 135 of the lifter 134 so that the latter lifts the link 176 as shown in Fig. 8 thereby withdrawing the claws 173 from engagement with the caps in the magazine allowing these to shift downwardly temporarily while the lowermost cap is being engaged by the vacuum cup 101. The added weight thus imposed on the lowermost cap causes the vacuum cup to be applied firmly thereto thus assuring a good suction between the cup

and this cap for effecting the downward stripping of the latter as the cup returns downwardly.

While Fig. 5 does not show the spring 102 compressed by engagement of the vacuum cup 101 with the lowermost cap it is to be understood that where the magazine contains a normal supply of caps, the weight of these imposed on the lowermost cap is sufficient to cause a further compression of the spring 102 as the plunger 86 moves upwardly. This prevents damage to the mechanism and assures a good suction contact between the cup 101 and the lowermost cap 21.

The screw 136 may be adjusted so as to delay the opening of the claws 173 so that when the cup 101 is lifted the group of caps 21 beneath the claws 173 are lifted into contact with the latter before these claws are swung outwardly. The claws 173 are thus caused to momentarily resist further upward movement of the cup 101 which results in the spring 102 being compressed and a good suction formed between the cap and cup.

I claim:

1. In a feeding device, the combination of: magazine means for holding a stack of flat articles; yieldable means for retaining said articles in said magazine means in stack form; vacuum cup means for separating an endmost article from said stack; and transverse feed means for engaging said article and shifting it parallel with the plane of said vacuum cup means and said stack.

2. In a feeding device the combination of: magazine means for holding a stack of flat articles one resting on top of the other; means for yieldably engaging a bottom-most article in said stack for supporting said stack of articles; vacuum cup means for separating the bottom-most article from said stack by pulling said article through said yieldable means; means for halting the travel of said bottom article with said cup means so that said article lies in a given plane; and means for causing said article to travel along a given transverse path from between said stack and said vacuum cup means.

3. In a feeding device, the combination of: magazine means for holding a stack of flat ar-

5
10

ticles, one resting on top of another; means for yieldably engaging the bottom-most article in said stack for supporting said stack of articles; a vacuum cup; means for reciprocating said cup into contact with said bottom-most article and then away from said stack; means for extracting air from said cup when the latter contacts said bottom-most article to cause the latter to be pulled downwardly through said yieldable means when said cup moves away from said stack; means for feeding an article thus stripped from said stack transversely from between said cup and said stack; and control means rendering said evacuation means inoperative to remove said bottom-most article from said stack when it is desired to skip the feeding of an article during a given reciprocation of said cup.

4. In a feeding device, the combination of: magazine means for holding a stack of flat articles, one resting on top of another; means for yieldably engaging a bottom-most article in said stack for supporting a bottom group of the articles in said stack; means for releasably supporting a reserve group of articles in said magazine means just above said bottom group; means for removing the bottom-most article from said stack by pulling it axially of the stack downwardly through said yieldable means; and means operable in timed relation with said article removing means to cause said releasable means to release a supply of caps from said reserve group to permit these to gravitate downwardly and join said bottom-most group of articles and then cause said releasable means to again support the balance of said reserve group.

FRANK W. KRUEGER.
